UNITED STATES PATENT OFFICE.

JOHN T. RIDDELL, OF EVANSTON, ILLINOIS.

INFLATABLE BALL.

Application filed March 12, 1926. Serial No. 94,111.

My invention relates to improvements in inflatable balls, such as footballs and basketballs, and has for its object the provision of an improved construction of this character provided with improved means for inflating the same.

Other objects will appear hereinafter.

The invention consists in the combinations and arrangements of parts hereinafter described and claimed.

The invention will be best understood by reference to the accompanying drawing forming a part of this specification, and in which;

Fig. 1 is a side view shown partially in section of a football embodying the invention; and,

Fig. 2 is an enlarged transverse section taken on line 2—2 of Fig. 1.

The preferred form of construction as illustrated in the drawing comprises the usual inner inflatable rubber member or bag 3 enclosed in the usual leather cover 4, having the usual gap or slit in one side thereof closed by the usual lacing 5. So much of the construction is old and well known, being the ordinary football construction and the same constitutes no part of my present invention except in so far as the same operates with the parts to be presently described.

The inner inflatable rubber member 3 is provided with an inwardly projecting valve stem 6 for inflating the same. This valve stem is preferably formed of aluminum or other light metal, having an outer head or flange 7 and a nut imprisoning and securing a rubber flap or flange 6' to said valve stem.

In assembling and making up the inflated member 3, the same is first formed in sections afterwards assembled and vulcanized together. To one of these sections the valve stem 6 and the flap 6' is applied and vulcanized thereto by means of suitable heat before the sections of the member 3 are assembled together. The valve stem 6 is provided with an ordinary readily removable spring-held check valve 9 equipped with the usual rod 9' for opening the same. The

valve stem 6 is provided at its outer end with internal threads 10 to permit of the ready insertion and removal of the check valve 9 and also to receive a fitting connected with an air pump or other means for supplying air under pressure for inflating the member 3 in the usual way. The

member 3 is also provided with loops or straps 11 through which the lacing 5 may be passed to hold the member 3 in proper position in the cover 4 so that the valve 60 stem 6 will always be opposite the opening or slit in said cover.

When it is desired to inflate the ball a suitable air pump or other source of air under pressure is connected with the valve 65 stem 6 through the medium of the internal threads 10 and air under pressure forced into the member 3 until the desired degree of pressure therein is attained. Then the air pump is disconnected, the valve 9 automatically closing and sealing the valve stem 6 against the escape of the air under pressure. When it is desired to deflate the ball the air is permitted to escape by simply pressing inwardly on the rod 9' thus 75 opening the valve 9 and permitting the escape of the confined air. At any time, when necessary, a new check valve may be substituted for the old one. In this way the ball may be uniformly inflated or deflated without materially disturbing the lacing 5 and a highly efficient seal, preventing the escape of the confined air, obtained owing to the fact that the internal pressure forces the valve 9 to its seat so that the greater the internal pressure the greater the force holding the valve to its seat. The valve stem being entirely enclosed in the ball itself is entirely protected thereby and the inflation of the ball when in use prevents contact of the valve stem with the inner walls of the ball. The specific form and arrangement of parts is a simple and effective one for the purpose.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having thus described my invention, what I claim as new and desire to secure by Letters Patent is:

1. An inflatable ball comprising an outer cover and an inner rubber inflatable member; a valve stem arranged entirely within said inflatable member and projecting into the interior thereof, said valve stem hav-

ing a rubber flap secured thereto and said rubber flap being in turn secured to the inner wall of said inflatable member; and a spring held check valve in said valve stem, substantially as described.

2. An inflatable ball comprising an outer cover and an inner inflatable rubber member; a valve stem secured to a wall of said inflatable member and projecting into the interior thereof, said valve stem having an outer head and a cooperating nut, a rubber flap being imprisoned between said head and nut, said rubber flap being vulcanized to the inner wall of said inflatable rubber member;

and a spring held check valve in said valve stem, substantially as described.

3. An inflatable ball comprising an outer cover and an inner rubber inflated member; a valve stem arranged entirely within said inflatable member and projecting into the interior thereof, said valve stem being secured to the wall of said inflatable member to lie entirely within said inflated member; and a spring-held check valve in said valve stem.

In testimony whereof I have signed my name to this specification.

JOHN T. RIDDELL.
